UNITED STATES PATENT OFFICE

FELIX J. WATTS, OF BRONSON, MICHIGAN, ASSIGNOR TO HARRY A. DOUGLAS, OF BRONSON, MICHIGAN

ELECTRIC SWITCH

Application filed August 8, 1930. Serial No. 473,824.

My invention relates to electric switches and has for its general object the simplification of the structure and operation thereof.

The switch of my invention is inclusive 5 of two abutments, a member cooperating with said abutments in controlling a circuit, said member and said two abutments being relatively spring pressed into engageability and being relatively rotatable upon 10 an axis passing between the abutments, said member having a recess receiving one of said abutments when the switch is adjusted to circuit opening position and then being tiltable upon the other abutment toward the 15 first, and a stop for limiting the extent of tilting movement of said member to maintain the circuit open. A switch casing desirably encloses the operating parts of such a switch, the aforesaid stop being preferably 20 the wall of the casing.

The invention will be more fully explained in connection with the accompanying drawings in which Fig. 1 is a longitudinal sectional view of the preferred embodiment 25 of the invention, parts being shown in elevation; Fig. 2 is a front view of part of the structure shown in Fig. 1, on a smaller scale; Fig. 3 is a sectional view on line 3—3 of Fig. 1; Fig. 4 is a sectional view on line 30 4—4 of Fig. 1; Fig. 5 is a sectional view on line 5—5 of Fig. 1; Fig. 6 is a view similar to Fig. 5 showing a changed position; and Fig. 7 is a perspective view of some of the 35 elements in separated relation.

35 The abutments 1 and 2 are desirably rigid being preferably inner continuations of metallic sleeves 3 and 4 which pass through a carrier 5 and are riveted into engagement with such carrier as illustrated. Circuit 40 conductors 6 and 7 enter the bores of said sleeves and are secured in place by binding screws 8 and 9. The carrier 5 is preferably an insulating disc which constitutes the closure wall of the cup shaped casing portion 10. The end wall of this cup shaped 45

casing portion has a central opening there-through which is margined by a sleeve continuation 11 of said end wall, this sleeve continuation terminating in a flange 12 which clamps the mounting 13 against the end wall of the cup. The member which cooperates with the abutments in controlling the circuit is desirably inclusive of a metallic plate 14 which serves as a bridging member when it engages said abutments. This plate is adapted to be turned into circuit opening and circuit closing position by means of the illustrated handle. This handle is formed in two sections, a metallic section 15 and an insulating section 16. Said insulating section extends to the exterior of the casing and is there knurled in order that it may be turned. This insulating section desirably has a square recess 17 which receives the correspondingly shaped portion 15. A spring 18 bears against the end wall of the recess 16 at one end and against the shoulder portion within the handle portion 16 at the other end. The handle part 15 is provided with an oblong portion 19 where it is surrounded by the plate. The opening 20 in the plate 14 is so shaped as to afford slight lost motion between such plate and the handle in order that the plate may finish each of its circuit adjusting movements 75 with a snap. The handle part 15 is provided with a further continuation 21 which is desirably cylindrical and is in sliding engagement with the wall 5 within an opening in such wall that closely fits the part 21. 80 The spring 18 serves to press the handle part 16 outwardly to a distance limited by the flange 22 on the handle part 16 that engages the end wall of the cup part 10. Said spring also presses upon the plate 14, through the 85 intermediation of the handle part 15, to hold this plate against both of the abutments 1 and 2 to close the circuit or against one of these abutments and the wall 5 to open the circuit, said wall then serving as a stop. 90

The plate 14 is provided with ridges 23, 24, 25 and 26 to separate the different places of engagement of the abutments 1 and 2 with the plates. When the circuit is closed one of the abutments is between the ridges 23 and 26 and the other abutment is between the ridges 24 and 25, the two parts of the plate engaged by the abutments being desirably coplanar. When the circuit is opened one of the abutments is between the ridges 23 and 25 and the other abutment is between the ridges 24 and 26. The material of the plate between the ridges 24 and 26 is not coplanar with the material of the plate between the ridges 23 and 25 but is rather recessed, so that when the switch is in circuit opening position, the abutment between the ridges 24 and 26 cannot engage the plate. Due to such recessing the spring 18 will tilt the plate 14 when the switch is open, but the wall 5 will limit such tilting movement to prevent it from reaching a degree in which the abutment between the ridges 24 and 26 would be ultimately engaged.

Changes may be made without departing from the invention:

Having thus described my invention, I claim:

1. An electric switch including two abutments; a member cooperating with said abutments in controlling a circuit, said member and said two abutments being relatively spring pressed into engageability and being relatively rotatable upon an axis passing between the abutments, said member having a recess receiving one of said abutments when the switch is adjusted to circuit opening position and then being tilttable upon the other abutment toward the first; and a stop for limiting the extent of tilting movement of said member to maintain the circuit open.

2. An electric switch including two metallic contact abutments; a plate cooperating with said abutments in controlling a circuit, said plate and said two abutments being relatively spring pressed into engageability and being relatively rotatable upon an axis passing between the abutments, said plate having a recess receiving one of said abutments when the switch is adjusted to circuit opening position and then being tilttable upon the other abutment toward the first; and a stop for limiting the extent of tilting movement of said plate to maintain the circuit open.

3. An electric switch including two abutments; a member cooperating with said abutments in controlling a circuit, said member and said two abutments being relatively spring pressed into engageability and being relatively rotatable upon an axis passing between the abutments, said member having a recess receiving one of said abutments when the switch is adjusted to circuit opening position and then being tilttable upon the other

abutment toward the first; a stop for limiting the extent of tilting movement of said member to maintain the circuit open; and formations upon said member separating the different places of engagement of the abutments therewith to hold the switch in its alternative adjustments.

4. An electric switch including two abutments; a plate cooperating with said abutments in controlling a circuit, said plate and said two abutments being relatively spring pressed into engageability and being relatively rotatable upon an axis passing between the abutments, said plate having a recess receiving one of said abutments when the switch is adjusted to circuit opening position and then being tilttable upon the other abutment toward the first; a stop for limiting the extent of tilting movement of said plate to maintain the circuit open; and formations upon said plate separating the different places of engagement of the abutments therewith to hold the switch in its alternative adjustments.

5. An electric switch including two abutments; a member cooperating with said abutments in controlling a circuit, said member and said two abutments being relatively spring pressed into engageability and being relatively rotatable upon an axis passing between the abutments, said member having a recess receiving one of said abutments when the switch is adjusted to circuit opening position and then being tilttable upon the other abutment toward the first; a stop for limiting the extent of tilting movement of said member to maintain the circuit open; and ridges upon said member separating the different places of engagement of the abutments therewith to hold the switch in its alternative adjustments.

6. An electric switch including two abutments; a plate cooperating with said abutments in controlling a circuit, said plate and said two abutments being relatively spring pressed into engageability and being relatively rotatable upon an axis passing between the abutments, said plate having a recess receiving one of said abutments when the switch is adjusted to circuit opening position and then being tilttable upon the other abutment toward the first; a stop for limiting the extent of tilting movement of said plate to maintain the circuit open; and ridges upon said plate separating the different places of engagement of the abutments therewith to hold the switch in its alternative adjustments.

7. An electric switch including a casing; two abutments upon a wall of and within the casing; a switch handle extending between the interior and exterior of the casing and rotatable upon an axis passing between said abutments; a member within the casing, said member and said abutments being rela-

tively spring pressed into engageability, said member having a recess receiving one of said abutments when the switch is adjusted to circuit opening position and then being tiltable upon the other abutment toward the first; and a stop for limiting the extent of tilting movement of said member to maintain the circuit open.

8. An electric switch including a casing;
- 10 two metallic contact abutments upon a wall of and within the casing; a switch handle extending between the interior and exterior of the casing and rotatable upon an axis passing between said abutments; a metallic plate 15 within the casing, said plate and said abutments being relatively spring pressed into engageability, said plate having a recess receiving one of said abutments when the switch is adjusted to circuit opening position and then being tilttable upon the other abutment toward the first; and a stop for 20 limiting the extent of tilting movement of said plate to maintain the circuit open.

9. An electric switch including a casing;
25 two abutments upon a wall of and within
the casing; a switch handle extending be-
tween the interior and exterior of the casing
and rotatable upon an axis passing between
said abutments; a member within the casing,
30 said member and said abutments being rela-
tively spring pressed into engageability, said
member having a recess receiving one of
said abutments when the switch is adjusted
to circuit opening position and then being
35 tiltable upon the other abutment toward the
first; a stop for limiting the extent of tilting
movement of said member to maintain the
circuit open; and formations upon said mem-
ber separating the different places of en-
gagement of the abutments therewith to hold
40 the switch in its alternative adjustments.

10. An electric switch including a casing; two abutments upon a wall of and within the casing; a switch handle extending between the interior and exterior of the casing and rotatable upon an axis passing between said abutments; a plate within the casing, said plate and said abutments being relatively spring pressed into engageability, said plate having a recess receiving one of said abutments when the switch is adjusted to circuit opening position and then being tilttable upon the other abutment toward the first; a stop for limiting the extent of tilting movement of said plate to maintain the circuit open; and formations upon said plate separating the different places of engagement of the abutments therewith to hold the switch in its alternative adjustments.

60 11. An electric switch including a casing; two abutments upon a wall of and within the casing; a switch handle extending between the interior and exterior of the casing and rotatable upon an axis passing between said abutments; a member within the cas-
65

ing, said member and said abutments being relatively spring pressed into engageability, said member having a recess receiving one of said abutments when the switch is adjusted to circuit opening position and then being tiltable upon the other abutment toward the first; a stop for limiting the extent of tilting movement of said member to maintain the circuit open; and ridges upon said member separating the different places of engagement of the abutments therewith to hold the switch in its alternative adjustments.

12. An electric switch including a casing; two abutments upon a wall of and within the casing; a switch handle extending between the interior and exterior of the casing and rotatable upon an axis passing between said abutments; a plate within the casing, said plate and said abutments being relatively spring pressed into engageability, said plate having a recess receiving one of said abutments when the switch is adjusted to circuit opening position and then being tiltable upon the other abutment toward the first; a stop for limiting the extent of tilting movement of said plate to maintain the circuit open; and ridges upon said plate separating the different places of engagement of the abutments therewith to hold the switch in its alternative adjustments.

13. An electric switch including a casing; two abutments upon a wall of and within the casing; a switch handle extending between the interior and exterior of the casing and rotatable upon an axis passing between said abutments; a member within the casing, said member and said abutments being relatively spring pressed into engageability, said member having a recess receiving one of said abutments when the switch is adjusted to circuit opening position and then being tilttable upon the other abutment toward the first; a stop for limiting the extent of tilting movement of said member to maintain the circuit open; and ridges upon said member separating the different places of engagement of the abutments therewith to hold the switch in its alternative adjustments, there being lost motion relation between the handle and the member permitting rapid conclusion of circuit changing movement.

14. An electric switch including a casing; two abutments upon a wall of and within the casing; a switch handle extending between the interior and exterior of the casing and rotatable upon an axis passing between said abutments; a plate within the casing, said plate and said abutments being relatively spring pressed into engageability, said plate having a recess receiving one of said abutments when the switch is adjusted to circuit opening position and then being tilttable upon the other abutment toward the 137

first; a stop for limiting the extent of tilting movement of said plate to maintain the circuit open; and ridges upon said plate separating the different places of engagement of the abutments therewith to hold the switch in its alternative adjustments, there being lost motion relation between the handle and the plate permitting rapid conclusion of circuit changing movement.

10 In witness whereof I hereunto subscribe my name.

FELIX J. WATTS.
